UNITED STATES PATENT OFFICE.

JOHN W. STROHM, OF NEW YORK, N. Y.

TARGET-PRACTICE APPARATUS.

1,369,572.

Specification of Letters Patent. Patented Feb. 22, 1921.

Application filed August 1, 1919. Serial No. 314,798.

To all whom it may concern:

Be it known that I, JOHN W. STROHM, citizen of the United States, and resident of New York city, in the county of New York 5 and State of New York, have invented certain new and useful Improvements in Target-Practice Apparatus, of which the following is a specification.

My invention relates to improvements in target practice apparatus and the main object thereof is to provide a simple and efficient form of apparatus which may not only be cheaply manufactured but is easy to set up and operate and not likely to get out of order. A further feature of the invention 15 is the provision of an apparatus which may be easily folded into a suitable case whereby it is conveniently portable. Further objects, features and advantages will more 20 clearly appear from the detail description given below taken in connection with the accompanying drawings, which form a part of this specification.

In the drawings Figure 1 is a perspective 25 illustrating an apparatus embodying my improvements in a preferred form thereof and set up ready for use. Fig. 2 is a detail side view of the pointer thereof. Fig. 3 is a plan view of the case opened and showing the apparatus folded therein. Fig. 4 is a side view 30 of the apparatus as shown in Fig. 1 with the aiming device removed. Fig. 5 is a plan view of the means to which the aiming device is connected. Fig. 6 is a plan view of 35 the removable end of the case.

Referring to the drawings 7 represents a box-shaped case of suitable size having a cover 8 extending over the biggest portion of the top thereof and which is hinged to 40 the case or box proper at 10 and 11. The bottom of the box or case is indicated at 12 and to the front edge thereof is journaled a member 13 by means of hinges 14 and 15, so that the member 13 is adapted to swing 45 laterally with respect to the case or base 7, about a single axis. The member 13 is provided with an arm 16 to the end of which is secured a metal plate 17 provided with a V shaped notch to form a fulcrum to engage a 50 V shaped notch 18 in a metallic plate 19 secured to a member 20. Pivoted secured to the member 20 at 21 and 22 respectively, are two parallel rods 23 and 24 adapted to swing in slots 25 and 26 in metal plates 27 55 and 28 secured to the front edge of the mem-

ber 20. The rods 23 and 24 are provided with hooks at their outer ends adapted to engage eyes secured to the side of the aiming device 28' so that each of the rods 23 and 24 is also pivotally connected to the 60 aiming device which with the member 20 forms substantially a parallelogram. A spring 29 has one end connected to the member 13 and the other end to the inside of the base box 7 and tends normally to swing the 65 member 13 about its axis in a direction to pull it into the box 7.

It will thus be seen that the aiming device which in the present instance is shown as a rifle may be moved a considerable distance in any direction, while the spring 29 will take up any slack between the parts and maintain the member 20 fulcrumed to have a universal movement on the fulcrum member 17. A counter-weight 30 is connected 70 to one end of a rod 31 which is connected to the member 20 by having the other end of the rod 31 pass through screw-eyes 32 and 33 until it abuts a pin 34, as more clearly shown in Fig. 5. This counter-weight 30 75 substantially balances the weight of the member 20 and other parts on the opposite side of the fulcrum 17.

The member 13 is also provided with an arm 35 to which is pivotally secured at 36, 80 a target frame 37 containing a transparent sub-target 38. A link 39 has its lower end pivoted to the side of the box 7 and its upper end pivoted to the target frame 37, the pivot points being in such relation that as the 85 member 13 is swung about its axis rotation of the target frame 37 with respect to the base box 7 is prevented, and the target frame is always maintained in a vertical position.

The member 13 is also provided with an arm 40 to the upper end of which is rigidly secured a metal plate member 41 provided with a V shaped knife edge notch forming a fulcrum for a pointer 42 having a V 100 shaped knife edge notch part 43 engaging the member 41 so that the pointer 42 is fulcrumed to have a universal movement in the V shaped notch member 41. The pointer 42 is provided with a counter-weight 44 so 105 that the pointer is nearly substantially balanced when resting at its fulcrum 41, but so balanced that the end 46 of the pointer will always rest at the bottom of target frame 37 when part 48 does not touch the 110

pointer. The weight 44 also tends to prevent rotation of the pointer no matter into what position the member 13 is swung. The end of the pointer at 46 is adapted to move 5 adjacent and in slight contact with the sub-target 38 being pressed very lightly thereagainst by intermediate spring members connected together by a member 45. The pointer 42 is also provided with a depending 10 knife edge 47 adapted to be engaged by a V shaped knife edge notch in a metallic member 48 secured to the end of member 20. As shown in Fig. 4 the axis on which the member 13 is journaled is not quite parallel 15 to the bottom of the box 12, but although inclined is substantially horizontal so that when I speak of the various axes being horizontal, I mean substantially horizontal as distinguished from vertical.

20 Member 20 is so constructed that a line joining the two fulcrum points at the outer ends of rods 23 and 24 if extended would intersect a line drawn through fulcrum points at 19 and 48, at the vertical plane of the 25 main target. The fulcrum points at members 41, 17 and the pivot point at 36 all lie in the same axial line, and this axial line and the axis about which the member 13 is adapted to swing laterally and the axis of 30 the aiming device 28' when properly aimed, all meet at substantially a common point in the plane of the main target aimed at, which target is not shown for lack of space. The aiming device is so constructed that a line 35 through the two fulcrum points adjacent the aiming device on the ends of rods 23 and 24, if extended would intersect a line through the front and rear sights of the aiming device at the same point on the main 40 target. The pointer 42 is so constructed that the point 46 is the same distance vertically above the extended line 43-47 as the bull's eye in the sub-target 38 is above the pivot 36. It will, therefore, be readily apparent 45 to those skilled in the art that the gun or aiming device 28' may be moved in any direction (within certain limits) not only vertically and laterally but horizontally as well, and when it is aiming correctly at the 50 main target, the notch member 48 will engage the knife edge 47 and raise the pointer and position it so that its end 46 will register with the center of the sub-target 38 and it will always so register whenever the aiming device is aimed correctly at the main 55 target. The aiming device may be moved so as to swing the member 20 about the V shaped notch in member 17 as a pivot, but so long as it continues to aim correctly at the 60 main target, the member 48 engaging the knife edge on the pointer 42 will maintain the end 46 of the pointer in register with the center of the sub-target, but should the aiming device 28' be moved in any direction so that it aims at some other point on

the main target, the member 48 will move the pointer 42 so as to throw the end 46 thereof away from the center of the sub-target to a corresponding extent and in this way the aim taken is always registered and 70 indicated by the pointer coöperating with the sub-target 38. Whenever the aiming device or gun 28' is fired an observer can easily notice by close watch of the pointer 75 42 with respect to the sub-target just where the shot has hit on the main target or if blanks are fired, where the shot would have hit if the discharge was not blank. Or if the gun is not actually fired the apparatus 80 will indicate where a shot would hit the main target when the trigger of the gun is pulled, as if a shot had actually been fired from the gun. It will be noted that the end of the pointer at 46 extends within the frame 37 so that the movements of the 85 pointer are somewhat limited and confined substantially to the area of the sub-target. This serves to prevent the pointer from being swung unduly and thereby injured. It will be noted that the pointer is easily removable from the other parts since it merely rests on the fulcrum member 41 and likewise the member 20 may be easily removed from the other parts since it merely rests on the member 17 and it may be disengaged 90 from the aiming device by merely unhooking the bars 23 and 24 from the latter. 95

When it is desired to fold the apparatus for transporting, the pointer and member 20 are removed as above explained, and then 100 the cover 8 thrown open. The spring 29 is unhooked from the member 13 and hooked in the box in the position shown in Fig. 3. The rod 31 and the counterweight 30 carried thereby, are then slipped out from the 105 screw-eyes 31 and 33 and it is placed in the bottom of the box and secured therein by means of a latch 50. The member 13 is then swung down into the box until it, together with the sub-target 38 and its frame 37 110 occupy the positions shown in Fig. 3. The pointer 42 is then placed in the case with its large end resting in a groove 51 and its small end 46 resting in a groove 52 as shown in Fig. 3. The cover 8 may then be closed 115 and screwed into place and thereupon the end cover member comprising an end piece 54 and a top piece 55 may be put in place, the top piece 55 lying over the ends of 56 and 57 (see Fig. 1) while the end piece 54 fits down between the ends of sides 58, 58 and 59. A block 60 is secured to the top piece 55 and engages the member 13 to hold it firmly in folded position and prevent it from swinging while folded in the box. The 120 end piece 54 is provided with grooves at 61 and 62 to accommodate the hinges 14 and 15 respectively and with a groove 63 to accommodate the end of the member 19. When the end cover is thus put on it may be 125 130

screwed into place and all parts will be neatly and securely packed in the case 7 which serves as a base for the apparatus when in use. It may be mentioned however, 5 that in order to secure the member 20 in place in folded position in the box it is provided with apertures 64 and 65 through which bolts 66 and 67 carried by the member 13 are adapted to pass when the parts 10 are in folded position and nuts 68 and 69 screwed on to the ends of these bolts firmly hold the member 20 in position in the case so that it will not rattle about therein. It will be understood that any suitable electrical 15 or mechanical means may be associated with the sub-target and pointer to indicate electrically or otherwise record the aim at the time of firing or at any given instant.

In setting up the apparatus either the base 20 box 7 or the main target may be moved and adjusted until such point is reached that when the aiming device is pointing accurately at the center of the main target the pointer 42 will be pointing accurately at 25 the center of the sub-target 38. Ordinarily the distance between the main target and the apparatus will be determined beforehand by the construction of the apparatus although this may be varied to some extent 30 without materially affecting the accuracy of the apparatus. If the main target is not accurately placed but only a short distance away from where it should be, the apparatus can be adjusted by moving the rear 35 sight on the gun 28' up or down or to the right or left sufficiently to cause the pointer 46 to register in the center of the bull's eye of the sub-target when the proper aim has been taken on the main target thereby enabling one with this device to trace the 40 corrections necessary if he aims correctly at the main target but does not hit the center of the bull's eye. It will be seen from the above that the apparatus permits of great 45 freedom of movement of the aiming device and yet it consists of very few parts, easily constructed and put together. The parts are preferably made out of light material such as wood and aluminum, although if 50 desired the base box may be made relatively heavy. The sub-target may be made of glass or other transparent material such as celluloid so that it may be satisfactorily viewed from either side thereof. Also if 55 desired the member 17 may extend up about the forward edge of the plate 19 fitting close thereto and so that a universal joint will be effected between the two which will not become unlocked by the movements occurring 60 in the use of the apparatus. With such modification the spring 29 may be omitted, so that there will be no spring tension tending to move the gun to one side.

While I have described my improvements 65 in great detail and with respect to a pre-

ferred embodiment thereof, I do not desire to be limited to such details or embodiment since many changes and modifications may be made and the invention embodied in widely differing forms without departing 70 from the spirit and scope thereof particularly in its broader aspects.

What I claim and desire to secure by Letters Patent is:—

1. In an apparatus of the class described 75 the combination of a relatively fixed base, a member pivoted on said base to swing laterally about a single axis with respect to said base, a sub-target carried by said member at one end, a fulcrum carried by said member at the other end, a fulcrum carried by said member intermediate said last mentioned fulcrum and said target, an aiming device, a member fulcrumed on said intermediate fulcrum, parallel links connecting 80 said last mentioned member with the aiming device, said links being pivoted with respect to the said last mentioned member and with respect to the aiming device, and a pointer 85 fulcrumed on said end fulcrum, said second member being adapted to engage said pointer to move it with respect to the sub-target as the aiming device is moved in aiming.

2. In an apparatus of the class described 95 the combination of a relatively fixed base, a member journaled to swing laterally with respect thereto, a sub-target and two fulcrums carried by said member, a pointer cooperating with said sub-target and fulcrumed on one of said fulcrums, an aiming 100 device and means connected to the aiming device and fulcrumed on the other fulcrum and adapted to engage said pointer to move it with respect to the sub-target in accordance with movements of the aiming device in aiming.

3. In an apparatus of the class described 105 the combination of a relatively fixed base, a member journaled to swing laterally with respect thereto, two fulcrums carried by said member, an aiming device, means fulcrumed on one fulcrum to have a universal movement with respect thereto and connected with the aiming device, a pointer fulcrumed on the other fulcrum and engaged by said means whereby it is moved in accordance with the movements of the aiming device, a sub-target pivotally carried by said aiming device and a link pivotally connected 110 to the sub-target and to the base.

4. In an apparatus of the class described 115 the combination of a relatively fixed base, a member journaled to swing laterally with respect thereto, a sub-target and two fulcrums carried by said member, a pointer cooperating with said sub-target and fulcrumed on one of said fulcrums, an aiming 120 device and means connected to the aiming device and fulcrumed on the other fulcrum 125

and adapted to engage said pointer to move it with respect to the sub-target in accordance with movements of the aiming device in aiming, said fulcrums comprising a V shaped knife edge notches.

5. In an apparatus of the class described the combination of an aiming device, a sub-target, a pointer coöperating therewith, a fulcrum for the pointer comprising a V shaped knife edge notch and means connected with said aiming device for giving said pointer a universal movement about its fulcrum in accordance with movements of the aiming device.

15 6. In an apparatus of the class described the combination of an aiming device, a sub-target, a pointer coöperating therewith, means connected with said aiming device for moving said pointer in accordance with movements of the aiming device, and means fulcruming said pointer comprising a V-shaped notch member on the pointer coöperating with a V-shaped notch fulcrum member.

25 7. In an apparatus of the class described the combination of an aiming device, a sub-target, a pointer coöperating therewith, means connected with said aiming device for moving said pointer in accordance with movements of the aiming device and means fulcruming said connecting means comprising a V shaped notch member on the connecting means coöperating with a V shaped notch fulcrum member.

35 8. In an apparatus of the class described the combination of an aiming device, a sub-target, a pointer coöperating therewith, means connected with said aiming device for moving said pointer with respect to the sub-target in accordance with movements of the aiming device and means fulcruming said last mentioned means comprising a V shaped notch member coöperating with a V shaped notch on said connecting means.

45 9. In an apparatus of the class described the combination of an aiming device, a sub-target, a pointer coöperating therewith, means connected with said aiming device for moving said pointer in accordance with movements of the aiming device, and engaging said pointer through a V shaped notch.

10. In an apparatus of the class described the combination of a relatively fixed base, a member journaled to swing laterally with respect thereto, a sub-target and two fulcrums carried by said member, a pointer coöperating with said sub-target and fulcrumed on one of said fulcrums, an aiming device and means connected to the aiming device and fulcrumed on the other fulcrum and adapted to engage said pointer to move it with respect to the sub-target in accordance with movements of the aiming device in aiming.

65 11. In an apparatus of the class described

the combination of a relatively fixed base, a member journaled to swing laterally with respect thereto, a sub-target and two fulcrums carried by said member, a pointer coöperating with said sub-target, an aiming device and means connected to the aiming device and fulcrumed on the other fulcrum and adapted to engage said pointer to move it with respect to the sub-target in accordance with movements of the aiming device in aiming, said means and pointer being removable from said fulcrums respectively, and from one another.

12. In an apparatus of the class described the combination of a relatively fixed base, a member journaled to swing laterally with respect thereto, a sub-target and two fulcrums carried by said member, a pointer coöperating with said sub-target and fulcrumed on one of said fulcrums, an aiming device and means connected to the aiming device and fulcrumed on the other fulcrum and adapted to engage said pointer to move it with respect to the sub-target in accordance with movements of the aiming device in aiming.

13. In an apparatus of the class described the combination of a case, a member journaled with respect thereto and adapted to swing into the case, a sub-target, a pointer coöperating with the sub-target and means adapted to be connected to an aiming device and said member to operate the pointer in accordance with movements of the aiming device, said case being adapted to inclose said means, pointer, sub-target and member when the latter are folded therein.

14. In an apparatus of the class described the combination of a case, a member journaled with respect thereto and adapted to swing into the case, a sub-target carried by said member, a pointer coöperating with the sub-target, and means adapted to be connected to an aiming device and said member to operate the pointer in accordance with movements of the aiming device.

15. In an apparatus of the class described the combination of a member journaled to swing laterally about a substantially horizontal axis, a sub-target carried thereby, a pointer fulcrumed to have a universal movement on said member and coöperating with said sub-target, and means fulcrumed on said member and adapted to be connected to an aiming device and to operate the pointer in accordance with movements of the aiming device.

16. In an apparatus of the class described the combination of a member journaled to swing laterally about a substantially horizontal axis, a sub-target carried thereby, a pointer fulcrumed to have a universal movement on said member and coöperating with said sub-target, and means fulcrumed on said member and adapted to be connected to

an aiming device and to operate the pointer in accordance with movements of the aiming device.

17. In an apparatus of the class described 5 the combination of a member journaled to swing laterally about a substantially horizontal axis, a sub-target carried thereby, a pointer fulcrumed to have a universal movement on said member and coöperating with 10 said sub-target, and means fulcrumed on said member and adapted to be connected to an aiming device and to operate the pointer in accordance with movements of the aiming device, and engaging said pointer through 15 a V shaped notch.

18. In an apparatus of the class described the combination of a relatively fixed base, a member adapted to swing laterally on said base, an aiming device, means connecting 20 the aiming device with said member, a pointer operated by said means and fulcrumed on said member, and a sub-target coöperating with said pointer, the axial line of said member, the axial line of said two 25 fulcrums and the axial line of the aiming device, all substantially meeting at a common point substantially at the target aimed at.

19. In an apparatus of the class described,

a sub-target, a pointer coöperating therewith, a fulcrum on which said pointer is adapted to have a universal movement, means adapted to be connected with an aiming device and having a part engaging said pointer to move it with respect to the sub-target and having a universal movement with respect to the pointer, and a fulcrum for said means and about which it has universal movement.

20. In an apparatus of the class described, 40 a sub-target, a pointer coöperating therewith, a fulcrum on which said pointer is adapted to have a universal movement, means adapted to be connected with an aiming device and having a part engaging said 45 pointer to move it with respect to the sub-target and having a universal movement with respect to the pointer, and a fulcrum for said means and about which it has universal movement, said means being adapted 50 to lift the pointer off of its fulcrum when the aiming device is moved to aim in a direction too wide of the mark.

Signed at New York city, in the county of New York, and State of New York, this 31st 55 day of July, A. D. 1919.

JOHN W. STROHM.
